UNITED STATES PATENT OFFICE.

DORSETT A. DAVISON, OF RICHMOND, VIRGINIA.

WINDOW.

1,117,954.

Specification of Letters Patent. Patented Nov. 17, 1914.

Application filed February 6, 1914. Serial No. 816,973.

To all whom it may concern:
Be it known that I, DORSETT A. DAVISON, a citizen of the United States, residing at Richmond, in the County of Henrico, State 5 of Virginia, have invented certain new and useful Improvements in Windows; and I do hereby declare the following to be a full, clear, and exact description of the invention, such as will enable others skilled in the art 10 to which it appertains to make and use the same.

This invention relates to certain novel and useful improvements in windows, and has particular application to that class of 15 windows wherein a sash or sashes may be swung from a substantially vertical to a substantially horizontal position, or vice versa, to regulate the amount of ventilation, to permit ready, convenient and safe access to the 20 glass for cleaning, and for other purposes.

In the present instance I propose to provide a structure wherein a sash or sashes, may be readily manipulated to swing the same to a selected angle for any desired purpose, and furthermore, I provide means 25 whereby the sash may be automatically held or fastened at a desired inclination relative to the window frame.

Still a further object of my invention is 30 the provision of devices whereby the liability of displacement or injuries to the working parts of the window, under the stress of sudden jars, such as would be due to gusts of wind and the like, is avoided.

35 I also aim to provide a window of this class which will embody in its construction the desired features of simplicity, efficiency and convenience.

With the above recited objects and others 40 of a similar nature in view, my invention consists in the construction, combination and arrangement of parts set forth in and falling within the scope of the appended claims.

45 In the accompanying drawings: Figure 1 is a perspective view of a window embodying my invention, the sashes being shown as swung inward to a horizontal position. Fig. 2 is a view partly in elevation and partly in 50 vertical section, and showing the sashes as slightly swung or tilted. Fig. 3 is a horizontal cross sectional view taken through a portion of the window frame and showing the position of the side bars of the upper 55 and lower sashes when the windows are in

vertical position, this view also illustrating the position of the sliding follower plates relative to the metallic guide strips of the window frame. Fig. 4 is a view similar to Fig. 3, showing but one of the sashes and 60 the adjacent portion of the window frame, and illustrating the sash as slightly tilted. Fig. 5 is a horizontal cross sectional view taken on line 5—5 of Fig. 2. Fig. 6 is a similar view of Fig. 5, but showing the sash 65 in its vertical or non-tilted position. Fig. 7 is a detail perspective view of one of the follower plates. Fig. 8 is a similar view of one of the hinge plates of the sash. Fig. 9 is a perspective view of the bottom portion 70 of one of the side bars of the sash and showing the same in substantially horizontal position when open to its greatest extent, this view illustrating the manner in which the shouldered end of the flange 8 bears against 75 the adjacent flange of the frame strip 4 to prevent further downward movement of the sash.

Before entering into a detailed description of my invention, I will briefly describe 80 the construction of the preferred form of my invention illustrated herein, and as the devices for one sliding and swinging sash are similar in construction to the devices of the other sash, a description of one will suffice 85 for both.

It will be noted that I have arranged at opposite sides of the window frame, metallic guide strips which extend the entire length of the frame. Each of these strips 90 is provided with oppositely disposed, outwardly turned flanges. To the outer face of each side bar of the window sash I fasten a strip, one of the longitudinal edges of which is provided with an out turned flange. Slid- 95 ing upon each guide strip of the window frame is a pivot plate having a pivot pin, and this pin is embedded in and engages the lower portion of the adjacent side bar of the sash. Also sliding upon each guide strip of 100 the window frame is a follower plate, to which is attached one end of one of the sash cords of the window. This plate has also pivotally connected therewith one end of a link bar, the opposite end of said link bar 105 being pivoted to the adjacent side bar of the sash. The pivot plates at the lower ends of the sash are formed with apertures 24, as shown in Fig. 8 which when the window is vertically disposed receive the locking stud 110

25 on the adjacent side bar of the sash and hold the window closed, the grip or pressure of these studs against the plate being also sufficient to hold the latter in tilted position,
5 so that it requires a positive effort to change the inclination of the window sash. Furthermore, each of the sliding follower plates is provided with tongues which are ordinarily out of contact with the adjacent side
10 wall of the guide strip of the window, on which such follower plates slide, but when the window is jarred or shaken suddenly, as by a gust of wind, these tongues will strike against the adjacent wall of the window frame strip and act as a break or stop, thereby reducing the liability of the window glass being broken.

Referring to the drawings in detail the letter A indicates the window frame as an
20 entirety, at each vertical side of which is a parting bead 1 and the sash stops 2 forming vertical grooves 3. Extending longitudinally the entire length of each groove and fastened to the bottom wall thereof is a metallic guide strip 4 which is approximately U-shaped in cross section and is provided with out-turned flanges 5 at the longitudinal edges thereof. In the present instance the upper sash of the window is designated
25 by the letter U, and the lower sash by the letter L, and as the construction and arrangement of the devices for each window sash is the same, a description of one will apply to both. Each window sash is provided
30 with the usual side bars 6, and to the outer face of each side bar I fasten a metallic strip 7 having an out-turned flange 8 extending along one longitudinal edge thereof. Each flange is cut or broken away near
35 the top of the sash as at 9, for the purpose of accommodating the follower plate 10, when the window is in its closed or vertical position so that a weather-tight joint is at all times formed between the window frame
40 and the sash. There are, of course, two follower plates for each sash, these follower plates being at opposite sides of the window frame, and sliding upon the adjacent strips 4. The construction of each follower plate
45 is shown in detail in Fig. 7, and as will be seen, comprises a flat or plate-like body portion having the vertical in-turned flanges 11 at opposite sides, which flanges engage and ride upon the out-turned flanges 5 of the window frame strip 4. The plate is provided
50 with a short top arm 12 which is off-set from the plate as at 13, this arm 12 having an eye 14 to which is attached one end of the sash cord 15. The plate is also formed with a
55 lower arm 16 having an eye 17 adapted to receive the pivot 18 which connects the upper end of the link bar 19 with the arm 16, the lower end of this link bar 19 being pivoted as at 20 to the adjacent side of the
60 sash at approximately the center of the lat-
65

ter. Sliding upon each of the window frame strips 4, below the follower plate 10, is a pivot plate 21, each of these pivot plates having the oppositely disposed vertical in-turned flanges 22 which ride upon the flanges 5 of the window frame strips. Each of these plates 21 carries a pivot pin 23 which extends through the bottom portion of the adjacent metallic strip 7 of the sash and into the lower portion of the adjacent side bar of the sash. In other words, the sash is pivotally mounted at the bottom portion thereof upon the pivots 23 carried by the pivot plates 21, so that such sash may swing from a vertical to a horizontal position, and vice versa, upon these pivots 23.

As will be seen by reference to Figs. 5 and 6, each side bar strip 7 is provided with a stud 25 which enters the bore or aperture 24 formed in the adjacent pivot plate when the window is in its vertical position, and the sash is therefore, locked against displacement or swinging. When, however, a pull is given to the sash to swing or tilt the same, the studs or projections 25 will be forced out of the aperture 24 and will bear against the adjacent surface of the plate 21, and bind to a certain extent, as shown in Fig. 5, so that the window will be maintained at a tilted position when the pull or pressure upon the sash is relieved. That is to say it will take a positive pressure or pull to tilt the sash, and when such pressure or pull is released that sash will be maintained in whatever tilted position it may occupy, by reason of the fact that the stud 25 is binding against the plate 21. This dispenses with the necessity of employing complicated means for locking the window in a predetermined position.

To prevent the glass of the window from being broken or shattered by an accidental jar, or shock, which might be due to any cause, such as a gust of wind, or sudden slamming of the window, I provide the follower plates 10 with the inwardly projecting tongues 26 which are approximately V shaped in form, and are positioned so that normally they lie near to, but spaced apart from the adjacent wall of the window frame strip. Now, should the window be jarred for any reason, the follower plate is likely to be shifted slightly laterally relative to the window frame strip upon which it slides, and immediately this takes place the tongues will be forced against the adjacent wall of the window frame strip, and act as a stop to prevent further lateral movement of the follower plate, and consequently prevent the displacement and breaking of the window. These tongues are useful in this connection because as the follower plates fit loosely on their guide strips so as to slide freely thereon, there is necessarily a certain amount of lateral or sidewise play per-

mitted between the follower plates and their strips. This play is limited and to a great extent prevented by the tongues.

From the above description, taken in connection with the accompanying drawings, the construction and operation of my improved swinging window will be readily apparent. When the window is closed the sashes occupy the usual vertical position, and under such conditions the link bars 19 lie parallel with the sides of the window frame, and the follower plates 10 are positioned on the guide strips of the window frame so that they fit within the cutaway portions 9 of the strips fastened to the side bars of their respective sashes. If it is desired to open the window by tilting the sash the sash is pulled inward, and such pulling action forces the studs 25 of the sash bars out of the apertures 24, so that such studs bind against the side faces of the pivot plates. Therefore, when the pull upon the sash has ceased, as when it has been tilted to the desired position, such sash will be held in such tilted position. Of course, as the sash is tilted inward, the follower plates 10 of such sash slide downward upon the guide strips of the window frame, as is shown in Figs. 1 and 2, the window sash itself turning with the pins 23 as its pivots. When the sash is completely closed or in its vertical position, the in-turned flanges 8 of the side bar strips 7 fit over the flanges 5 of the window frame guide strips 4 and thereby form a water-tight joint.

Referring to Figs. 9 of the drawings, wherein I have shown one position assumed by one of the side bars of the sash when the sash is completely open or thrown to a horizontal position, it will be seen that the flange 8 of the sash bar strip 7 near its lower end is formed with a stop lug 8' so that when such sash bar is swung to a horizontal position, the lug 8' of the flange 8 will abut against the edge of the adjacent flange 5 of the window frame strip, and therefore such strip will act as a stop and prevent the window sash from swinging downward past or beyond the horizontal position.

It will be noted that by reason of the divergence of the sides of the plates 4, when the sliding members are pressed apart by the action of the studs before referred to, these diverging sides will tend to flatten out or spread or to further diverge, and when they thus flatten out or spread, their free edges are brought into intimate contact with the sliding plate and held with sufficient friction to positively insure against sliding movement of the sliding plates.

It will be noted that I have provided an exceedingly simple, yet efficient type of swinging window, embodying but relatively few parts, and these are so constructed that

they are not liable to get out of order or be easily injured.

While I have herein shown and described one particular embodiment of my invention, I wish it to be understood that I do not confine myself to all the precise details of construction herein set forth by way of illustration, as modification and variation may be made without departing from the spirit of the invention or exceeding the scope of the appended claims.

What I claim is:

1. The combination with a window frame, of a swinging vertically sliding sash, a sash strip extending longitudinally of one side 80 of the sash, a traveling follower connected with the sash, and a guide strip located at one side of the window frame and constituting a track upon which the follower slides and engaged by the sash strip to form a 85 weather-tight joint when the window sash is in its vertical closed position.

2. The combination with a window frame, of a guide strip located at one side thereof, a pivot plate sliding upon the guide strip, 90 a window sash pivotally connected with the pivot plate, a follower plate sliding upon the guide strip of the window frame and attached to the sash cord of the sash, a link connecting the follower plate with the window sash, and means for locking the sash in tilted position, said means including a projection on the sash adapted when the sash is in vertical position to seat in a socket in the side of the pivot plate and 100 designed when the sash is in tilted position to bear against and force the pivot plate into binding engagement with the guide strip.

3. The combination with a window frame, 105 of a guide strip located at one side thereof, a pivot plate sliding upon the guide strip, a window sash pivotally connected with the pivot plate, a follower plate sliding upon the guide plate of the window frame and attached to one of the sash cords of the sash, a link connecting the follower plate with the window sash and a tongue projecting from the follower plate and adapted to form a stop for contacting with the guide strip 115 of the window frame when the follower plate is shifted laterally.

4. The combination with a window frame, of a guide strip located at one side thereof and provided with a pair of oppositely disposed outwardly extending flanges at the longitudinal side edges thereof, a relatively flat pivot plate sliding upon the guide strip and having inturned flanges engaging with the out-turned flanges of the guide strip, a 120 window sash pivotally connected at its lower end with the pivot plate, a relatively flat follower plate sliding upon the guide strip and having inturned flanges engaging with the flanges of the guide strip, said follower 125

plate having one of the sash cords attached thereto, and a link pivotally connected at one end to the follower plate and at its opposite end to the side of the window sash.

5. The combination with a window frame, of a guide strip located at one side thereof and having oppositely disposed lateral flanges extending longitudinally thereof, of a pivot plate sliding upon the guide strip and having flanges engaging with the flanges of the guide strip, a window sash pivotally connected with the pivot plate, a sash strip extending longitudinally of one side of the sash and having a longitudinal edge flange,

10 15 a follower plate sliding upon the guide strip and a link pivotally connecting the follower plate with the sash, said strip acting as a track for the follower plate and cooperating with the sash strip to form a weather-tight joint when the sash is in closed position.

15 20 6. The combination with a window frame, of a guide strip located at one side thereof

and provided with out-turned flanges, a pivot plate sliding upon the guide support, 25 a window sash pivotally connected with the pivot plate adjacent to its lower portion, a strip attached to the side bar of the sash and provided with in-turned flanges adapted to engage with the out-turned 30 flanges of the guide strip, said in-turned flanges of the guide strip having their lower portions bent to form stops for limiting the downwardly swinging movement of the sash, a follower plate sliding upon the guide 35 strip of the frame, said follower plate being attached to the sash cords of the window frame, and a link pivotally connecting the follower plate with the window sash.

In testimony whereof, I affix my signature, in the presence of two witnesses.

DORSETT A. DAVISON.
